SWITCH STRUCTURE

Albert E. Gerth and George F. Embshoff, Cincinnati, Ohio, assignors to Institutum Divi Thomae Foundation, Cincinnati, Ohio, a corporation of Ohio

Application September 13, 1956, Serial No. 609,627

12 Claims. (Cl. 200—144)

The invention has to do with switch structures particularly designed for the handling of heavy amperages at high frequencies, as in the switching of radio frequency currents. A significant though non-limiting application for the invention lies in the field of "vacuum switches," which term as herein used means switches the operating elements of which are enclosed in an evacuated or fluid-filled envelope, usually of glass. The invention will be described in an exemplary embodiment having to do with such switches.

It is a primary object of the invention to provide improvements in switches designed to handle high amperages at high frequencies which improvements greatly increase the capacity of the switches to handle such currents without increasing the size of the switch assembly.

Since the operating elements of such switches (hereinafter for convenience termed electrodes) tend to reach relatively high temperatures in operation both because of the high amperages involved and because of the skin effects of high frequencies if the switches are heavily loaded, it is an object of the invention to provide structures in which the currents are carried more efficiently, and in which the effects of high temperatures are minimized.

These and other objects of the invention which will be clear to the skilled worker in the art upon reading these specifications or will be pointed out hereinafter are accomplished by that structure and arrangement of parts of which the aforesaid embodiment will now be described. Reference is made to the accompanying drawings wherein:

Figure 1 is a longitudinal vertical section of a vacuum switch embodying the invention.

Figure 2 is an end elevation thereof.

Figure 3 is a partial sectional view showing the mode of operation of the movable electrode.

Figure 4 is an enlarged partial section taken along the line 4—4 of Figure 1.

Figure 5 is an enlarged partial section taken along the line 5—5 of Figure 3.

Figure 6 is a partial perspective of the contact end portion of the movable electrode as such.

Figure 7 is a partial perspective of the contact end of the movable electrode with the strip elements in place.

Figure 8 is a partial perspective of the contact end of one of the strips in the exemplary embodiment.

Figure 9 is a partial perspective view of the same end of the other of the strips.

In the figures, 1 designates the glass envelope of a vacuum switch device having opposed openings 2 and 3 and a transverse opening 6. Stationary electrodes 7 and 8 are sealed in the opposed openings 2 and 3. The inner ends of these electrodes approach each other axially and bear contact members such as molybdenum contacts 9 and 10. Between the opposed ends of the stationary electrodes is located the contact end of a movable electrode 11 bearing a contact element 12 of suitable metal and operating in such fashion that the

2

contact 12 may be brought selectively into contact with either of the contact elements 9 or 10.

The manner in which the stationary electrodes 7 and 8 are mounted with respect to the glass envelope is not a limitation on the broader aspects of this invention. The stationary electrodes, being normally made of some metallic substance such as Kovar suitable for sealing to glass, may be mounted directly in the openings 2 and 3 in the envelope with the glass fused about them, as has hitherto been usual in this art. For heavy duty switches, however, it is preferred to mount the electrodes 7 and 8 at the center portions of relatively thin flange-like elements or flares 13 and 14 to which the electrodes are joined in a gas-tight fashion as by hydrogen-brazing. The flare elements have rims 13a and 14a, and, being made of a metallic material suitable for sealing to glass, are mounted in the envelope 1 in such a way that the glass at the openings 2 and 3 is sealed directly to the rims of the flare elements. Such a structure and the method of making it are described in detail in the copending application of Albert E. Gerth entitled Mounting for Electrodes in Glass Vessels, Serial No. 605,121 filed August 20, 1956. The mounting of the electrodes in the glass envelope by means of the aforesaid flare elements is useful in permitting the electrodes to reach higher operating temperatures without adversely affecting the seals to the glass envelope.

The transverse electrode 11 may be mounted, as such, in the usual fashion. As illustrated in the drawings there is a metallic thimble 15, one end of which is closed by a metallic diaphragm member 16. The diaphragm member has a rim 16a engaging an end of the thimble and hydrogen-brazed or otherwise joined thereto in a gas-tight fashion. The electrode 11 passes through the center of the diaphragm member and is joined thereto in a gas-tight fashion as by brazing. The diaphragm, being flexible, permits a limited movement of the electrode 11 as a lever, furnishing a fulcrum for such movement. The opposite end of the thimble 15 is joined to the neck of the glass envelope at the transverse opening 6, the glass being sealed to the metal of the thimble as indicated at 17 in Figures 4 and 5.

It is conventional, moreover, in switches of this type to form the movable electrode of suitable metallic tubing, and to exhaust the vessel of envelope through the electrode 11 by connecting it with a suitable vacuum pump. When the desired vacuum has been attained in the vessel, the electrode 11 is pinched as at 11a and welded or otherwise sealed to prevent re-entry of gas. Normally a getter substance is applied to a support 18 within the envelope and is fired by the application of inductive heating through the envelope, in order to clean up the last traces of the atmosphere therein.

The manner in which the switch may be operated is by movement of the movable electrode 11. It will be seen that the structure is in effect a single pole, double throw switch.

The electrode 12, usually though not necessarily in the shape of a rectangular piece of suitable metal, such as molybdenum, is affixed to the end of the movable electrode 11 inside the envelope. There are various ways in which this may be done. One way is illustrated in Figure 6. The end of the tube is slotted, the contact member 12 is thrust within the slot, and the walls of the tube are welded to both sides of the contact member as at 19 and 20. In order to exhaust the vessel through the electrode 11 the slot is left open at the bottom, or a lateral opening 21 is provided therethrough if the inner end of the electrode is closed by the attachment of the contact member.

In the practice of the invention use is made of a pair of strips joined with the movable electrode. These strips

have their upper end portions formed or stamped as at 22 and 23 to surround the electrode 11. Excepting at the top, their lateral edge portions may be flared as at 24 and 25 so as to form fin-like structures. The upper portions of the strips may thus be placed around the movable electrode and fastened together by spot welding or otherwise as indicated at 26 and 27 in Figure 7.

The strips, juxtaposed as indicated, substantially surround the whole length of the movable electrode within the envelope and the thimble.

The lower end portions of the strips (in flat condition) are reversely bent upwardly as at 28 and 29 in Figure 5 and then again reversely downwardly as at 30 and 31 so that their ends lie along inner surfaces of the thimble 15, to which they may be caused to conform, and to which they may be joined as by spot welding, brazing or in other ways. The reversely bent portions of the strips provide by flexing for movement of the movable electrode in the operation of the switch.

The upper end of one at least of the strips is carried upwardly beyond the end of the contact element 12 and is provided with a cut-out 32 disclosing the central portion of the contact element. The outer end portion of the contact element is fastened to the projecting portion of the strip as by spot welding at 33. Instead of making the extending portion a part of one of the strips, it could be made separately and fastened by welding between the ends of the strips 22 and 23.

The strip structure described has several functions. It assists in the carrying of the current applied to the movable electrode 11. It provides additional current carrying paths between the movable electrode and the thimble 15, to which contact may be made, thus relieving the diaphragm member of some current carrying duty. Because of the greatly enlarged surfaces of the strip structure the carrying of high frequency currents is made more efficient. Moreover the strips act to some extent as radiators and conductors of heat, permitting the electrode to operate more effectively. The fin-like conformation above described assists in this. The current is transferred in part to the contact element 12 through its lower end by the movable electrode 11; but current also flows through the extending end portion of the longer strip about the opening 32 and is transferred to the upper end of the contact 12 at the connection 33. This increases the efficiency of electrical transfer to the contact member, and minimizes heating effects.

Modifications may be made in the structure described as exemplary without departing from the spirit of the invention. The use of the invention is not confined to the movable electrode in a structure of the class described but may be applied instead or in addition to other electrodes. The strip structure may, if desired, be brazed or welded to the electrode with which it is associated, but this is not normally necessary.

Having described the invention in an exemplary embodiment, what is claimed as new and is desired to be secured by Letters Patent is:

1. In electrical apparatus of the class described, a metallic, current-carrying electrode of elongated form, a metallic mounting means therefor to which a portion of said electrode is attached, and from which said electrode extends in one direction, and at least one current carrying strip element lying along the said extent of said electrode and affixed to said electrode, said strip element having a free end attached to said mounting means.

2. The structure claimed in claim 1 wherein said electrode carries at one end a contact element affixed thereto and projecting therefrom, and in which a member united with the said strip element extends beyond and is elec-

trically joined with the projecting portion of said contact element.

3. The structure claimed in claim 1 including two opposed strip elements one on either side of said electrode and shaped to embrace said electrode.

4. The structure claimed in claim 1 including two opposed strip elements one on either side of said electrode and shaped to embrace said electrode, an electrical contact member attached to the end of said electrode, and one at least of said strips having a portion in electrical union therewith extending beyond said contact member and electrically joined to the projecting end thereof.

5. The structure claimed in claim 4 wherein the said extending portion is provided with an orifice to disclose said contact member.

6. In a structure of the class described, a vitreous envelope, an electrode having an end projecting into said envelope and sealed to said envelope through the intermediary of a metallic mounting means, and at least one conductive metallic strip having a portion lying along and affixed to the electrode within said envelope and another, reversely bent portion attached to said mounting means.

7. The structure claimed in claim 6 wherein a contact member is attached to the end of said electrode within said envelope so as to project from said electrode, and in which said strip is electrically joined to the projecting end of said contact member.

8. In a structure of the class described, an elongated movable electrode, a metallic thimble, a flexible metallic diaphragm across an end of said thimble, said electrode passing axially through said diaphragm, said diaphragm being flexible whereby said electrode is capable of rocking movement with respect to said thimble, and at least one metallic strip having a portion lying along said electrode and another reversely bent portion having an end attached to said thimble.

9. The structure claimed in claim 8 including a pair of strips wider than said electrode, one on each side of said electrode, each said strip having a reversely bent portion with an end attached to said thimble, side portions of said strips extending laterally beyond said electrode being separated to form fins.

10. The structure claimed in claim 9 wherein a contact member is attached to the end of said electrode and wherein a portion in electrical union with one of said strips extends to the projecting end of said contact member and is electrically joined thereto.

11. The structure claimed in claim 9 wherein a contact member is attached to the end of said electrode and wherein one of said strips extends to the projecting end of said contact member and is attached thereto, the projecting end of said strip being provided with an orifice to disclose said contact member.

12. The structure claimed in claim 9 wherein a contact member is attached to the end of said electrode and wherein one of said strips extends to the projecting end of said contact member and is attached thereto, the projecting end of said strip being provided with an orifice to disclose said contact member, in combination with at least one other electrode entering and sealed to said envelope through a heat-dissipating, thin-walled metallic mounting means, said last mentioned electrode having a contact element coacting with the first mentioned contact element.
